H. Higley,

Cultivator.

Patented Dec. 11. 1832.

Dec 11, 1832

Henry Highley, of Canaan, State of Connecticut,

Letters Patent.

The subject referred to in this Letter Patent are making part of the same, containing a description in the words of the said Henry Highley himself of his improvement in the plough & harrow to all to whom these Presents shall come

Be it known that I, Henry Highley of Canaan in the County of Litchfield & State of Connecticut, have invented a new and useful improvement in a machine or instrument called a Plough & Harrow, to be used for loosening the soil & destroying the weeds among crops of Corn, Cotton, and other crops, and for other agricultural purposes, and that the following is a full and exact description of the construction and operation of the said machine as invented or improved by me viz— The said machine or instrument is in its properties a combination of a plough and a harrow and consists of the following parts, — First a straight piece of timber about three inches square and about three feet long (marked A in the annexed plate) — Second two straight pieces of timber of the same size and dimension marked B, which are framed into said first piece on opposite sides of it, at or near its center at acute angles to it and to each other so that their extreme ends are about two feet and three inches apart, presenting the shape of the common harrow. Into each of said second pieces are inserted two teeth made either of cast or wrought iron standing perpendicular and projecting about seven inches from the under side of said pieces of timber, — Into each of said second pieces is also inserted on the upper side, a straight piece of timber about three feet long but at the upper end inclining back for a handle (marked D) and

the coulter are connected together by a rod running from one to the other in under said first piece of timber at or near the place where said second piece joins it is placed a share (share C) which is of the following form and dimensions viz: said share is made of one piece of iron about enough on each end to somewhat in the form of a double plough share and its two hakes as divided by a line running from the center of the nose to the center of the broadest end are perfectly alike. The nose is about three inches long and about one and a half inch wide it is of equal width. The width of the back or broadest end is about thirteen inches. The length from the center of the broadest end to the extremity of the nose is about thirteen inches from the nose to the extreme corner of the share on each side of the center edge is straight and the iron is brought to an edge. From this edge on each side it gradually rises towards the center so that the center at the back or broadest end is about five inches high. From the nose back it also rises in the center line before mentioned to the coulter or sword hereafter mentioned.

This center is also brought to an edge on the upper surface from the point to said coulter which edge also gradually rises from the point to said coulter and from said coulter to the center of the broadest end is of equal height and is a little flattened both on the under and upper surface. The under surface of said share is hollowing rising gradually from each side and from the nose towards the center so that the share is about an inch thick at the center and gradually grows thiner towards the edge the said share when detached from the instrument presenting the appearance shown by the figure in the annexed plan marked K. This share is attached to the barrow at ready mounted with the broadest end of the share turning

the broadest end of the harrow, and the center line of the share in a line with said first piece of timber and in the following manner, a bolt of wrought iron (marked G) passes through said first piece of timber just back of where said second pieces are joined to it and about four inches below the under side of it is bent forward, at a right angle and passes under the center of the share about five inches and a small bolt passing thru the share and thru this bolt it is fastened with a nut. A brace to this bolt (marked H,) made also of wrought iron passes thru said first piece of timber about eight inches back of said main bolt, and is joined to it at the place where it is bent, to pass under the share, about four inches forward of said main bolt is a coulter or sword (marked E,) the upper end of which passes thru the said first piece of timber and is fastened on the top of it with a nut, and the lower end passes thru the share and thru the end of said main bolt, and is fastened on the under side with a nut. On the forward end of said first piece of timber is placed a common, clevis (marked F,) by which it is to be drawn. This Machine is to be drawn by one or more horses or other beasts and to be used for ploughing, and harrowing among corn, cotton and any other crop planted in rows and for ploughing, and harrowing in, wheat and other kinds of grain and for any other agricultural purpose for which it can be profitably used, - What I claim as new and as my own invention or discovery in the machine herein before described and for the use of which I ask an exclusive privilege, is the share herein before described and the combination of the properties of the plough and the harrow, in the same instrument and performing the work of both by the same operation, - I sign at Caanan the 24th day of October A.D. 1832,

Witness, William P. Burwell,

W. M. Burwell,
